UNITED STATES PATENT OFFICE.

SIMEON SNIDER, OF PALATINE, ILLINOIS.

MILK-COOLER.

SPECIFICATION forming part of Letters Patent No. 599,644, dated February 22, 1898.

Application filed August 28, 1897. Serial No. 649,863. (No model.)

To all whom it may concern:

Be it known that I, SIMEON SNIDER, of Palatine, in the county of Cook and State of Illinois, have invented a new and Improved 5 Milk-Cooler, of which the following is a full, clear, and exact description.

My invention relates to an improvement in devices for cooling liquids, with a special reference to its use in connection with cooling 10 milk and cream, although the device is applicable to the cooling of any liquid.

Reference is to be had to the accompanying drawings, forming a part of this specification, in which similar characters of reference indicate corresponding parts in all the figures.

Figure 1 is a top plan view of my device. Fig. 2 is a cross-sectional elevation on the line 2 2 in Fig. 1, and Fig. 3 is a cross-sectional elevation on the line 3 3 in Fig. 2. 20 My device is used in connection with a flowing stream of water or other liquid, which is made to absorb and carry away heat from the liquid to be cooled. It comprises a tank A, made of any suitable size and shape, within 25 which the liquid to be cooled is placed. In the device as herein shown and described this liquid will ordinarily be referred to as "milk" or "cream," although the device may be used for cooling any other liquid. The two

30 opposite ends of the tank are provided with bearings A', which each receive a horizontal section of pipe B². This pipe immediately inside the edge of the tank is bent downward, so as to form the substantially vertical members B' and the horizontal members B³. The vertical portions B' are of such a length that the horizontal member B³ reaches substantially to the bottom of the tank when the pipe is oscillated. At one end of the pipe a 35 vertical nipple or short section is attached to one of the horizontal pivot-sections B², and a hose A² is connected thereto for supplying the water or other cooling fluid. To the other end of the pipe is connected a counterbalance-arm C, provided with a weight C', attachable 40 thereon at any point desired. The arm C extends in substantially the same direction as the members B' of the pipe. When the swinging portion of the pipe is thrown to one side 45 of the center, the weight C' will maintain the swinging portion of the pipe upon that side until power is applied thereto to shift it.

This power is applied to the pipe by means of cords G, which are fixed at one end upon the arm C and pass over pulleys g, supported 55 by brackets attached to boxes E on the tank A, and have buckets E' attached to their other ends.

The buckets E' are made to slide in the boxes E or in any suitable guideway and are 60 provided with ball-valves e in the bottoms thereof, said valves being retained in place by wickets or gratings e'. Each valve is attached to a cord e², which at its upper end is attached to a pin e³ at the top of the box E, 65 the cord being of such a length that when the bucket has descended to a certain point the valve will be raised from the bottom of the bucket and the further descent of the bucket stopped. Each bucket E' is provided with a 70 bail E², to which the cord G, connecting it with the counterweight-arm C, is attached. To the bail are also attached cords F', which extend over guide-pulleys f, supported by brackets attached to the boxes E, and are connected 75 at their upper ends with a bar F, pivoted to the free ends of the valve-levers d.

The pivot-sections B² of the pipe through which the water flows from the tank are connected to a pipe D, which extends in opposite 80 directions from the section B² and is provided at the sides of its connection with a pipe with valves d and d'. These valves are connected to the levers d² in such a manner that when the levers d² are held in one position 85 the valve d is opened and the valve d' is closed, and when the levers d² are thrown in the opposite direction, through the movements of the connecting-bar F, the valve d will be closed and the valve d' will be opened. 90 The continuations D' of the discharge-pipe are curved around, so as to discharge into one or the other of the buckets E'.

The position of the parts as shown in Figs. 1 and 2 is with the horizontal section B³ of 95 the cooling-pipe to the left. In this position the bucket E' upon the left side of the tank is raised and the valve d' is open. The water flowing through the cooling-pipe will thus be discharged into the bucket E' upon the left side of the tank. At the same time the bucket E' upon the opposite side of the tank and in its lowermost position has the valve e opened and is therefore empty of water. As

soon as the water in the bucket which is up becomes heavy enough to overcome the counterbalance-wight C' the bucket will descend and pull the arm C over to the position shown 5 in dotted lines in Fig. 2.

The bucket in its descent will stop when the cord e^2 , attached to the ball-valve e , is tightened. This will raise the valve and permit the water to flow out. As the bucket descends the cord F' acts upon the bar F , connecting the valve-levers, and shifts the valves, so that the water is discharged into the opposite bucket, which has been raised. This operation will continue automatically and will result in swinging the horizontal portion B^3 of the cooling-pipe from one side of the tank A to the other. This will result in stirring the contents of the tank and in shifting the cooling-pipe from one position to the other, thus facilitating the rapid cooling of the contents of the tank.

In the drawings the swinging portion of the pipe is shown as consisting of a single pipe. Instead of this construction, however, a coil of pipe or a flat receptacle may be used. The exact shape of this portion of the device is not material, the only point in this construction being to furnish a sufficient amount of surface to secure rapid cooling and also to stir the contents of the tank.

This device is simple in its construction and certain in its operation. It will continue automatically to operate as long as the supply of cooling-water is obtained. The water may be cooled artificially, if desired, or if more rapid cooling is desired than can be obtained by the use of water any cooling fluid desired may be substituted therefor. This cooling fluid cannot injure milk, because it does not come in direct contact with it, and there is no possibility of its getting into it.

Having thus fully described my invention, I claim as new and desire to secure by Letters Patent—

1. A milk-cooling device, comprising a tank, a pipe journaled on the sides of the tank and dropping between its journals into the tank, a connection from one end of said tank to a water-supply, and a shifting device operated by the escaping water to oscillate the pipe on its journals, substantially as described.

2. A milk-cooling device, comprising a tank, a pipe journaled on the sides of the tank and dropping between its journals into the tank, a connection from one end of said tank to a water-supply, branching connections extended in opposite directions from the other end of the pipe, a valve in each branch, a bucket having a valve in the bottom thereof mounted to rise and fall beneath the outlet of each branch, and connections from said buckets to the valves and to the oscillating

pipe whereby the same are operated, substantially as described.

65

3. A milk-cooling device, comprising a tank, a pipe journaled on the sides of the tank and dropping between its journals into the tank, a connection from one end of said pipe to a water-supply, branching connections extending in opposite directions at the other end of the pipe, a valve in each branch, a connection therebetween for operating the valves together, a bucket mounted to rise and fall beneath the outlet of each branch and having a puppet-valve in its bottom, a guiding-case surrounding the valves and connections from said buckets to the valves and to the oscillating pipe, whereby the same are operated by the descent of the bucket, substantially as described.

70

4. A milk-cooling device, comprising a tank, a pipe journaled on the sides of the tank, and dropping between its journals into the tank, a weighted arm attached to said pipe and extending opposite to the downwardly-dropping parts thereof, a connection from one end of said pipe to a water-supply, and a shifting device operated by the escaping water to oscillate the pipe on its journals, substantially as described.

75

5. A milk-cooling device, comprising a tank, a pipe journaled on the sides of the tank and dropping between its journals into the tank, a weighted arm attached to said pipe and extending opposite to the downwardly-dropping parts thereof, a connection from one end of said pipe to a water-supply, branching connections extending in opposite directions at the other end of the pipe, a valve in each branch, a bucket mounted to rise and fall beneath the outlet of each branch, and connections from said buckets to the valves and to the oscillating pipe, whereby the same are operated, substantially as described.

80

6. A milk-cooling apparatus, comprising a tank, a pipe journaled upon opposite sides of the tank and dropping into the tank intermediate its journals, a weighted arm connected to said pipe and extending opposite to that part of the pipe which drops into the tank, a water-supply connection to one end of said pipe, branching pipes connected to the other end, a valve in each branch, levers connected to said valves, a bar connecting said levers to maintain the two valves in opposite positions, a bucket in each branch receiving its discharge, connections from said buckets to the oscillating pipe and to the bar connecting the valve-arms, and a tappet-valve in the bottom of each bucket, opened by the descent of the bucket, substantially as described.
